UNITED STATES PATENT OFFICE

WALTER H. HALL, OF WINCHENDON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY

WOOD HEEL JACK

Original application filed January 4, 1928, Serial No. 244,530. Divided and this application filed April 15, 1929. Serial No. 355,221.

This invention relates to a jack used for clamping wood heel blanks in position for shaping in a wood heel molding machine and is a division of my prior application 5 Serial No. 244,530, filed January 4, 1928 and granted on June 10, 1930 as Patent No. 1,762,296.

The object of the invention is to improve the construction of jacks for the purpose stated and to provide an arrangement and combination of parts by which more effective operation may be secured.

Important features of the invention relate to improved means for clamping the blank 15 in the jack and for securely retaining the parts in clamping position.

A preferred form of the invention is shown in the drawings in which

Fig. 1 is a side elevation of a jack embodying my improvements; and

Fig. 2 is a similar view showing the parts in a different position.

Referring to the drawings, my improved jack comprises a frame member 10, secured 25 to the upper end of a supporting shaft 11 and having swinging movement about the axis of said shaft. A heel blank support 12 is pivoted at 13 to the stand 10. The support 12 has a bearing portion 14 engaging a cam member 15 and raised or lowered thereby as 30 the jack is swung about the axis of the shaft 11.

A frame member 17 is secured to the support 12 and extends upward therefrom. The 35 heel blank B rests on a serrated plate 20 on the support 12, and the upper surface of the heel blank is engaged by a clamping bar 21 having a cross pin or stud 22 loosely pivoted in a slot 23 in the frame member 17.

40 A hand lever 25 is pivoted at 26 on a lever arm 27, which in turn is pivoted at 28 to the frame member 17. A cam roll 30 on the hand lever 25 engages the upper surface of the clamping bar 21 as the handle is swung 45 downward and forces the clamping bar against the upper surface of the heel blank B.

An adjusting screw 32 is threaded in the upper end of the frame member 17 and acts as an adjustable abutment to limit upward 50 movement of the lever arm 27. The screw

32 thus constitutes means for controlling and adjusting the pressure on the heel blank B. A molding cutter is indicated diagrammatically at C and a usual stop plate at 60.

Having described the details of construction of my improved jack, the method of operation will be readily apparent. When the jack is opened to permit removal and replacement of a molded blank, the hand lever 25 is in the raised position indicated in Fig. 55 1 and the pressure of the cam roll 30 on the clamping bar 21 is released. The finished heel blank B may then be removed and a new blank may be inserted in the jack and will be positioned by the stop 60 which engages 60 an edge surface of the blank.

The hand lever 25 is then moved downward to the position indicated in Fig. 2, causing the roll 30 to apply rolling or cam pressure to the clamping bar 21 and to force the 70 same downward into firm engagement with the heel blank. As the hand lever approaches its lower limit of travel, the roll 30 passes beyond the line of a perpendicular from the pivot 26 to the upper surface of the arm 21, 75 and the re-action of the pressure applied to the heel blank thereafter serves to hold the parts securely in clamping position. The adjustment of the lever arm 27 by the screw 32 is direct and positive and all parts of the jack 80 are of simple construction and of ample strength and durability.

Having thus described my invention and the advantages thereof, I do not wish to be limited to the details herein disclosed, otherwise than as set forth in the claims, but what I claim is:—

1. In a wood heel jack, a heel blank support having an upward extension, a clamping bar pivoted on said support extension, a hand lever, an arm for said lever pivoted on said support extension and to said lever, a roll on said lever engaging said clamping bar, and means to adjust said lever arm relative to said support.

2. The combination in a wood heel jack as set forth in claim 1 in which the hand lever has a range of clamping movement sufficient to carry said roll to a locking position beyond the line of a perpendicular from the pivot of 100

said hand lever to the roll-engaging surface of said arm.

3. In a wood heel jack, a heel blank support having an upward extension, a clamping bar pivoted on said support extension, a hand lever, an arm for said lever pivoted on said support extension and to said lever, a roll on said lever engaging said clamping bar, and an adjusting screw for limiting upward movement of said lever arm relative to said support.

4. In a wood heel jack, a heel blank support having an upward extension, a clamping bar pivoted on said support extension, a hand lever engaging said clamping bar, an arm for said lever pivoted on said support extension and to said lever, and an adjusting screw threaded in the fixed upper end of said support extension and adjustable therein to vary the clamping position of said bar.

5. In a wood heel jack, a heel blank support having an upward extension, a clamping bar pivoted on said support extension, a hand lever engaging said clamping bar, an arm for said lever pivoted on said support extension and to said lever, and an adjusting screw for limiting upward movement of said lever arm relative to said support, said screw being mounted in the fixed upper end of said support extension and directly engaging said arm.

In testimony whereof I have hereunto affixed my signature.

WALTER H. HALL.

CERTIFICATE OF CORRECTION.

Patent No. 1,815,734.

Granted July 21, 1931, to

WALTER H. HALL.

It is hereby certified that the above numbered patent was erroneously issued to "United Shoe Machinery Corporation, of Paterson, New Jersey", whereas said patent should have been issued to Goodspeed Machine Company, of Winchendon, Massachusetts, a corporation of Massachusetts, said corporation being assignee of the entire interest in said invention, as shown by the records of assignments in this office; and that the said Letters Patent should be read with this correction therein that the same may conform to the record of the case in the Patent Office.

Signed and sealed this 22nd day of September, A. D. 1931.
